UNITED STATES PATENT OFFICE.

PATRICK B. DELANY, OF SOUTH ORANGE, NEW JERSEY.

TELEGRAPHY.

No. 894,820.

Specification of Letters Patent.

Patented Aug. 4, 1908.

Application filed May 23, 1907. Serial No. 375,199.

To all whom it may concern:

Be it known that I, PATRICK B. DELANY, a citizen of the United States, residing in South Orange, county of Essex, State of New Jersey, have invented certain new and useful improvements in Telegraphy, of which the following is a specification.

This invention relates to a system of telegraphy in which a plurality of dots is transmitted as a single impulse of a length corresponding to the number of dots it represents, and which at the receiver is disintegrated into the component dot signals. Such a system is disclosed in applications heretofore filed by me. In those applications are shown local electro-magnets interactingly controlled to effect disintegration of a received solid impulse of current into the dot signals it represents. Such local magnets, one controlling the circuit of another, effectively carry out the system referred to, which may of course be practiced in other ways.

The present invention deals with special apparatus and arrangements thereof to disintegrate solid impulses into their component short signals, that experience has shown to be particularly simple and effective.

In place of the interacting electro-magnetic apparatus referred to, an electro-magnetic mechanical dot maker is employed, its function at the sending end being to guide the operator by converting into dots or short signals, the long impulses representing a plurality of dots, and at the receiving end to perform the same functions under control of the relay for the delivery or transcription of the signal represented compositively by a long transmitted impulse.

In the accompanying drawings: Figure 1; shows the electro-magnetic mechanical dot maker as applied to the system of secret telegraphy over a single wire at the sending and receiving station and controlled by polarized relays; Fig. 2, shows its application to secret telegraphy over two wires and controlled by neutral relays; Fig. 3, shows it as applied to secret working according to the system used on cables.

Referring to Fig. 1, when key K at station A is pressed against contact c, one pole of the split battery b is connected to line L through wire w, polarized relay P, wire w', polarized relay P', main line L to polarized relays P², P³ and wire w² to earth at station

B. The effect of this impulse on polar relays P, P² is to hold their armature levers against stops s, s²; and at the same time the armature levers of relays P¹, P³ are moved to their stops s', s³. When these latter armature levers leave stops e, f, the normally closed local circuits of vibrators V, V' are opened. These vibrators each consist of an electro-magnet v, an armature v' carried by an arm v², supported by a spring blade v³ rigidly mounted in a fixed block v⁴. Above the armature the arm v² is provided with an adjustable sliding weight v⁵ by means of which the rate of vibration of the part v², v³ may be regulated. Normally the magnet v attracts the armature lever, putting the spring supporting-blade v³ under tension and holding the armature lever against its front stop v⁶. When the armature lever is released by the opening of the circuit of the magnet, the armature lever will make at each vibration contact with spring contact d, thereby closing and opening the circuits of the sounders S, S' making dots so long as the key K is held in closed position. When the lever K' is pressed against contact c' for a dash, the relays P, P² are energized by current from the other pole of battery b through wires h, i, w, line L and w² to earth, the armature levers of relays P¹, P³ being held firmly against their stops e, f. When the armatures of P, P² reach their stops j, k, the sounders S, S' are closed and remain so until lever K' has been released and the relay armatures are returned to their stops s, s² by their springs p, q, similar to the action of the armatures of the relays P, P³ after withdrawal of the current. In this way it will be seen that while the single impulses representing dots and of a length corresponding to the number of dots to be sounded or recorded are passing through the circuit, these impulses are being disintegrated or divided up into actual dots at both stations. This occurs with a degree of perfection unattainable by transmission of individual dots over the line. Furthermore, as the number of impulses sent over the line is reduced about thirty percent, and as those transmitted in most cases are of comparatively long duration, much longer circuits may be worked and at much higher speeds.

Fig. 2, represents the electro-magnetic mechanical auto-dot maker as applied to se-

cret telegraphy employing two wires, one for the dots and the other for the dashes, neutral relays being employed. When key K is pushed to contact c, the main battery b' is sent to the distant station via wire w³, relay R line L and relay R' to earth or battery. This impulse actuates relays R R' and when their armatures leave their back stops e' and f' the circuits of the magnets 5 of the electro-magnetic mechanical vibrators VV' are broken and the sounders S S' operated as already described in connection with Fig. 1. When lever K' is pressed to contact post c' for a dash, the current from battery b' goes to the distant station via wire w⁴, relay R², line L', relay R³ to earth or battery. The armatures of relays R², R³ close the sounders circuits as already 10 described. 15 Fig. 3, shows diagrammatically the electro-magnetic mechanical automatic dot maker applied to cables or lines operated on the cable plan, using dot signals for dashes as well as dots, the polarity of the impulses determining their character. When key K² is 20 pressed down for a dot, one pole of battery b² is connected to earth through wire w⁵, key K², lower contact bar k' and wire w⁶, leaving the other pole of the battery to line through wire w⁷, upper contact bar k² and key K³. Simultaneously with the transmission of this 25 impulse, the circuit of the automatic dot maker V² is broken at the insulated contacts l, l', where it is normally closed via wire w⁸, local battery m, magnet of vibrator V² and wire w⁹. So long as key K² is held down, the 30 vibrator V² will operate its sounder S⁴, so that if, for instance, four dots are to be transmitted, the operator holds the key down until 35 the sounder has sounded that number. Similarly when key K³ is pressed down, the circuit of automatic dot maker V³ is broken from its normally closed condition through insulated contacts n, n', wire w¹⁰, circuit of 40 magnet of vibrator V³, wire w¹¹, battery m, wires w⁸ and w¹². As in the case of automatic dot maker V², the vibrator of V³ is released and its sounder S⁵ actuated so long as key K³ is held down,—thus notifying the 45 operator when the requisite number of dots has been sent. The long impulses sent into the line may be received on relay P⁴ controlling vibrator V⁴ and its sounder S⁶. When the key K² is pressed down for a time, representing one or more impulses, the polarized 50 relay P⁴ will respond breaking the circuit of its vibrator V⁴ and producing dots on its sounder S⁶. When the dash key K³ is pressed down, polarized relay P² is actuated, 55 breaking the circuit of its vibrator V⁵, causing dots representing dashes to be made on its sounder S⁷. In this way, the long impulses representing a plurality of dots or dashes, are converted into their component 60 parts or signals corresponding with the num-

ber of dots made at the transmitting station by the vibrators V², V³. The sounders S⁶, S⁷ may if desired, repeat into another circuit. The sounders S⁶, S⁷ should have different tones, if the operator is receiving by sound, so that he may readily distinguish between the short signals that represent dots and the short signals that represent dashes. 70

Of course usual switches for connecting the apparatus for transmission or reception are to be provided. Such a switch is shown at X in Fig. 2.

I claim:

1. In telegraphy a transmitter having an elastic vibrator, a magnet normally maintaining the vibrator at rest under tension, a normally closed local circuit for said magnet, a signal manifesting instrument, its local circuit and contacts by which its circuit is controlled regularly by the vibrator when the latter is in operation, a key and transmitting source of electric energy and circuit connections and contacts whereby when the key is closed the vibrator magnet is deenergized and the vibrator released to vibrate at its regular normal rate and a continuous current sent to line, combined with a distant receiver having a like vibrator, normally energized magnet maintaining it under tension, a signal manifesting instrument controlled by the vibrator and a relay energized by said transmitted impulse and acting to open the normally closed circuit of the vibrator. 80 85 90 95

2. In telegraphy a transmitter comprising a key and transmitting source of electric energy an elastic vibrator normally maintained under tension and means whereby when the key is closed to the source of electric energy said vibrator is released to vibrate at its normal rate and a continuous signal impulse is transmitted, combined with a receiver having a relay actuated by said impulse and a like vibrator normally maintained under tension and released when the relay is actuated. 100 105

3. In telegraphy a transmitting key or member, a polarized relay and its source of energy controlled by said member, an automatic dot maker, its controlling electro magnet, and circuit connections whereby the circuit of the dot maker magnet is established while the armature lever of the polarized relay is in open position and broken when said lever starts to its closed position. 110 115

4. In telegraphy, a transmitter having a dot contact and a dash contact, electro-magnetic means controlled by said transmitter and its dot contact for holding inoperative against its normal retractile tension a circuit controlling vibrator, a main line, an electro-magnet in said main line at the receiving end, a source of electric energy controlled by said transmitter for actuating said electro magnet, means controlled by said electro-magnet for holding inoperative against its normal retractile tension a circuit controlling vibra- 120 125 130

tor, means controlled by said transmitter and said electro magnet for simultaneously putting into vibration the said two vibrators and means controlled by the vibrators to automatically produce corresponding short or dot signals at the sending and receiving ends of the main line.

In testimony whereof, I have hereunto subscribed my name.

PATRICK B. DELANY.
